UNITED STATES PATENT OFFICE.

LEOPOLD HERMAN FRANK, OF EAST ORANGE, NEW JERSEY, ASSIGNOR TO LEO DI REBAYLIO, OF NEWARK, NEW JERSEY.

ADJUSTABLE COVER FOR BOXES.

1,326,333.

Specification of Letters Patent. Patented Dec. 30, 1919.

Application filed February 6, 1919. Serial No. 275,415.

To all whom it may concern:

Be it known that I, LEOPOLD HERMAN FRANK, a citizen of the United States, residing at 22 S. Arlington Ave., East Orange, in 5 the county of Essex and State of New Jersey, have invented certain new and useful Improvements in Adjustable Covers for Boxes, of which the following is a specification.

10 This invention relates to adjustable hinged covers for boxes, and has for its object the production of a combination of parts of special construction and arrangement, whereby the lid or cover when raised or lowered may 15 be left in any position whatever without further attention. In other words, the box cover after being raised to any extent from its closed position will remain where left until it is again moved. Ordinarily, if one 20 hand is used to raise the cover of a box, the other hand must be used to make some adjustment to hold the cover in position, or else the cover must be opened to a predetermined extent and until it reaches a catch or some 25 similar devices which hold it in one particular position. It is often desirable to leave but a slight opening between the top of the box or other receptacle and its cover or lid, thereby allowing a restricted volume of air 30 to enter or humidity to escape as in drying chambers or the like; or to control the amount and character of issuing sounds as in the case of phonograph cabinets; or to govern the emission of light from lamp boxes, 35 and it is frequently desired to change such openings at will with as little trouble as may be practicable.

The accompanying drawings illustrate the construction and arrangement of the parts 40 of this invention, and Figure 1 of the drawings represents a perspective view of the interior of a box to which this invention has been applied, the lid or cover being shown as partly raised. Fig. 2 is a front view of 45 this invention, the side of the box being shown in vertical section on the broken line 2-2 of Fig. 1. In all the views after Fig. 1, the scale of drawing has been slightly increased. Fig. 3 is a view from the inside of 50 one corner of a box equipped with this invention, portions of the outer friction plate and its leather being broken away to disclose parts otherwise hidden from view,

Fig. 4 is an inside view of one corner of a box with this invention applied, showing 55 one form of spring to balance the lid. Fig. 5 is a view similar to Fig. 4 showing a modified form of lid spring. Fig. 6 is a view similar to Fig. 4 showing another form of 60 spring to act upon the cover or lid.

Throughout the drawings and description the same letter is used to refer to the same part.

Considering the drawings, Figs. 1, 2 and 3, the box A has the cover or lid a. The 65 cover is pivotally connected with the box by means of a sector plate B, attached to the cover, and having the curved slot b, and a pivotal joint C with the twin, parallel friction plates D and d. The pivotal joint 70 C connecting the sector plate and the friction plates is in fact the hinge or pivotal support for the cover of the box, and, it will be understood, as illustrated that a sector plate and friction plates are provided for 75 each of the two rear inner corners of the box at the top of the box.

The friction plates are secured to the side of the box by screws E, and an additional screw e, which may be termed a pressure 80 screw, passes through the outer friction plate D, through the curved slot b in the sector plate B, and into the underlying friction plate d. In other words, the sector plate B, provided with the curving slot b 85 moves between the two friction plates D and d, and the screw e is so placed that when the lid of the box is lowered the slot b, one end of which is open as illustrated in Fig. 3, takes in the screw e, which does not, therefore, interfere with the movement of the plate B. It is believed to be clear that if the screw e is set up, the leather friction lining sheets F and f, with which the inner surfaces 90 of the friction plates D and d are usually provided in practice, will be pressed more or less strongly against the sector plate B. The pressure of the screw e is opposed only by the integral spring connection c between the two friction plates D and d, and located 95 at the upper inner corner of the plates as best shown in Fig. 2. This invention is not intended to be limited to the particular construction of spring connection between the friction plates set out in the drawings. The 100 function of the spring connection is to sep- 105

arate the plates and relieve the friction pressure on the sector plate, when the screw *e* is loosened or unscrewed.

As set out in Fig. 3, the sector plate is usually formed with a lip *G* that contacts with a pin stop *g*, and prevents the cover of the box from being inadvertently thrown so high as to disengage the sector plate and friction plates.

- 10 Considering Fig. 4, which may be regarded as illustrating a box *H* having a lid *h* of the same structure as already described, and also the sector plate *J* on the cover and the friction plates *j* on the box as before.
- 15 In this figure a pivot rod *K* connects the sector plates at both rear corners of the box, and the coil spring *k*, having one end *L* bearing upon the cover, and the other end *l* lying against the back of the box, encircles the rod 20 and operates to balance the weight of the lid in any position. It will now be understood that, if the weight of the cover is relieved either in whole or in part, there need be less friction to hold the lid in place at 25 any point.

In Fig. 5 there is shown a modified lid and spring. The box *M* has the cover *m*, and the cover is provided with the sector plate *N* and friction plates *n*. The pivot rod *O* 30 carries a modified twisted spring *P*, having one end bearing against the inside of the cover, and the other end resting against the inside of the box *M*.

In Fig. 6 a still further modification of 35 the lid or cover spring is illustrated. The box *Q* has the cover *R*, with the sector plate *S* and friction plates *T*, all as before explained. The pivot rod *U* in this modification lies in the hollow of a grooved spring 40 plate *V*. This plate has one edge secured to the edge of the box, and the other edge to the edge of the cover *R* as shown.

The operation of this invention as set forth in all the different figures of the drawings is the same. The friction plates are 45 pressed against the sector plates sufficiently to hold the cover against its weight, or against its weight as balanced by the springs described, in any position to which it has 50 been raised, and it is not necessary to engage or to disengage any securing or catching devices to suitably adjust the cover. It is believed to be clear from the foregoing that while a light cover may demand but a light 55 or no cover spring, it is very convenient and useful to have a relatively heavy cover so balanced.

Having now described this invention and explained the mode of its operation, what I claim is:—

60

1. In an adjustable box cover, the combination with a box and lid therefor, of a sector plate attached to the said lid and movable therewith, friction plates secured to the box and arranged to receive the said sector 65 plate between them, the said sector plate and the said friction plates having a pivotal joint connecting them and forming the hinge or pivotal support of the said lid, and means for varying the pressure of the friction plates upon the said sector plate.

2. In an adjustable box cover, the combination with a box and lid therefor, of a sector plate attached to the said lid, a pair of friction plates arranged parallel to each 70 other and secured to the box, the said friction plates being also arranged to receive the sector plate between them, the said friction plates having an integral spring connection between them, the said spring connection tending to separate the plates, and means for varying the pressure of the friction plates upon the said sector plate.

3. In an adjustable box cover, the combination with a box and lid therefor, of a sector plate attached to the said lid, a pair of friction plates arranged parallel to each 75 other and secured to the box, the said friction plates being also arranged to receive the sector plate between them, the said friction plates having a spring connection between them located at one corner of the said plates, and means for varying the pressure of the friction plates upon the sector plate.

4. In an adjustable box cover, the combination with a box and lid therefor, of a sector plate attached to the said lid, a pair of friction plates arranged parallel to each 80 other and secured to the box, the said friction plates being also arranged to receive the sector plate between them, the said friction plates having a spring connection between them one with the other constructed to press them apart, means for varying the pressure of the friction plates upon the said sector plate, the 85 said friction plates having a pivotal joint connecting them and forming the hinge or pivotal support of the lid, a pivot rod passing through the said joint at each rear corner of the box, and a spring arranged to exert an opening pressure upon the lid.

In testimony whereof I affix my signature.

LEOPOLD HERMAN FRANK.
